UNITED STATES PATENT OFFICE.

BENJAMIN W. BROUWER, OF AUBURN, MASSACHUSETTS, ASSIGNOR TO CROMPTON & KNOWLES LOOM WORKS, OF WORCESTER, MASSACHUSETTS, A CORPORATION OF MASSACHUSETTS.

YIELDING BOBBIN SUPPORT FOR MULTICOLOR LOOM MAGAZINES.

Application filed July 30, 1926. Serial No. 125,852.

This invention relates to improvements in bobbins supports for weft replenishing mechanisms more particularly of the multi-color type, and it is the principal object of 5 the invention to provide a yieldable support for the butts of bobbins so designed as to have an extension on which the bobbin will be moved as soon as released from the supporting cradle.

10 In multi-color weft replenishing mechanisms the bobbins are usually arranged in a series of vertical compartments and there is usually a cradle or delivery device located at the bottom of each compartment effective to advance the bobbin toward transfer position. The bobbins roll down inclined yielding guides or supports after leaving the cradle and it has been found that when the bobbin strikes the support 20 it is subject to rebounding such as interferes with the proper movement of the same toward transfer position. It is a further object of my invention to prevent this rebounding by supplying the yielding support with a lip extending into the path of the bobbin to receive the latter as soon as it moves from the cradle toward transfer position.

In Patent No. 1,554,372 there is shown 25 a stationary support having an auxiliary run to guide the bobbin as the same passes from the cradle toward transfer position and in co-pending application Ser. No. 739,692 filed by Hume and King the forward support for the butt of the bobbin is shown as yieldable under a pressure considerably heavier than that which holds the rear support in position and it is a further object of my invention to construct the 35 yieldable support as shown in said application with the auxiliary run set forth in the aforesaid patent, the auxiliary run being so disposed that as the support yields under excessive pressure said auxiliary run will be clear of adjacent parts.

With these and other objects in view which will appear as the description proceeds, my invention resides in the combination and arrangement of parts hereinafter 45 described and set forth in the claims.

In the accompanying drawings wherein I have shown a convenient embodiment of my invention,

Fig. 1 is a vertical section through a

multi-color weft replenishing mechanism of 55 the usual type looking toward the center of the loom and showing my invention applied to the mechanism in normal position,

Fig. 2 is a detail horizontal section on line 2—2 of Fig. 1, 60

Fig. 3 is a diagonal section on line 3—3 of Fig. 1,

Fig. 4 is a vertical section on line 4—4 of Fig. 3, and

Fig. 5 is a perspective view of the support. 65

Referring to the drawings it will be seen that I have shown a loom frame 10 having a multi-color weft replenishing mechanism 11 provided with flanges 12 which define a 70 bobbin compartment 13. It is to be understood that there are several compartments in the usual type of mechanism, only one being shown herein. A so-called cradle 14 has one end thereof pivotally mounted as at 75 15 on the frame 11 and the other end of said cradle may be supported in the usual manner by structure not shown. Said cradle is provided with a yarn engaging body 16 extending under the weft to support the 80 bobbin. The cradle is further provided with a finger 17 somewhat shorter than that usually employed and serving to support that part of the butt of the bobbin which is toward the center of the replenishing mechanism. Under normal conditions the cradle 85 is to the right of the position shown in Fig. 1 and is not occupied by a bobbin but at the time of indication of weft exhaustion the cradle is rocked to occupy a position similar 90 to that shown in the drawings, whereupon the lowest bobbin B of the stack will fall into the cradle and be supported by the body 16. Upon the subsequent arrival of the indicating shuttle the cradle will be restored 95 to normal position by being given a right hand oscillation from the position shown in Fig. 1, this rocking of the cradle releasing the bobbin contained therein so that the latter will move toward transfer position. This 100 part of the structure may be substantially the same as is set forth in Patent No. 1,030,748.

There are usually provided two guides or supports for the butt of the bobbin, the rear support 18 being yieldable under comparatively light pressure to move rearwardly a slight distance at the time of transfer and a

considerable distance when the bobbin is not properly discharged from the magazine. This support is common and has been in use for many years and may be as shown in Patent No. 1,307,024.

The other yielding support 19 is substantially the same as that set forth in the aforesaid Hume and King application and comprises a hub 20 pivoted on a stud 21 secured in fixed position to the replenishing mechanism frame 11. Said support is provided with an inclined bobbin run 22 terminating in a depending lip 23, said runway 22 being preferably provided with a slight rib 24 which engages the rings on the butt of the bobbin to prevent endwise movement thereof away from the giveaway 19 when moving toward transfer position. The hub is connected to the bobbin run portion 22 by a stop portion 25 normally held against the bottom 26 of the frame 11 by means of a relatively heavy tension spring 27 the upper end of which is held by a pin 28 secured to the replenishing frame and the lower end of which passes under a lug 29 carried by the support 19 adjacent the stop portion 25. The spring 27 is heavy and is designed to yield only under excessive pressure such as occurs when a bobbin is caught between the transerrer arm 30 and the inclined run 22. Under normal transferring conditions the support 19 will be held as though rigid by the spring 27, and may be the same as set forth in the aforesaid co-pending application, said support representing a comparatively recent improvement in multi-color weft replenishing mechanisms.

My invention relates more particularly to a device for guiding a bobbin from the cradle to the inclined surface 22 and in carrying out my invention I extend one side of said giveaway forwardly and upwardly as indicated at 40, said extension having an upper surface 41 extending above the surface 22 as is indicated clearly in Fig. 4. Said extension also projects approximately to the horizontal center of the compartment 13 and lies close to the adjacent end of pin 17 of the cradle 14.

When the bobbin B is discharged from the cradle as previously described the wooden end 42 of the bobbin butt will engage the elevated surface 41 before the steel rings 43 of the bobbin engage the surface 22 and as the bobbin moves downwardly toward the shuttle S the rings will gradually roll onto the surface 22. In this way an abrupt sharp engagement of the steel rings with the giveaway surface 22 is avoided and there is therefore no tendency for the butt of the bobbin to rebound upwardly. It has been found in magazines as heretofore constructed that this upward rebounding retards the downward movement of the bobbin

to such an extent that the latter is not properly positioned above the shuttle at the time the transerrer arm engages the bobbin and the result is either a broken bobbin or a broken magazine. The extension 40 lies closely adjacent the frame 11 and is of considerably less width than the inclined surface 22 so that an appreciable length of pin 17 extends under the bobbin to support the same prior to delivery of the bobbin by the cradle to the support. It will be seen that the auxiliary guide or extension can move about stud 21 as a pivot without interfering with adjacent portions either of the magazine or the cradle.

From the foregoing it will be seen that I have provided a yielding support for a multi-color weft replenishing mechanism having an auxiliary run or guide for the bobbin lying intermediate the cradle and the primary guiding surface of the support, and effective to cause the bobbin to be delivered to the main run by a gradual movement which will prevent rebounding of the bobbin. Furthermore, it will be seen that the extension is free to move about the stud 21 without interfering with the cradle, said extension projecting at least as far as the center of the compartment 13 and receiving the wooden end 42 of the bobbin before the rings 43 engage the surface 22.

In the aforesaid Richardson patent there was an opportunity for the rings of the bobbin to strike the upper end of the main guideway but as shown in Fig. 4 herein the surface 41 of the auxiliary guide extends further above the main surface 22 than the rings project beyond the wooden part of the butt of the bobbin and that said inclined surface 41 is tapered gradually to merge with the surface 22 as shown in Figs. 4 and 5.

Having thus described my invention it will be apparent that changes and modifications may be made therein by those skilled in the art without departing from the spirit and scope of the invention, and I do not wish to be limited to the details herein disclosed but what I claim is:

1. In a loom weft replenishing mechanism having a bobbin compartment and a pivoted cradle having a bobbin supporting portion positioned to control the delivery of bobbins from the compartment toward transfer position, a bobbin support pivoted to the replenishing mechanism and having a downwardly inclined surface, and an auxiliary guide extending from the support and being of less width than the support and lying closely adjacent to but out of the path of the supporting portion as the cradle pivots, said guide extending into the path of a bobbin which is passing from the cradle toward the support to guide the bobbin onto the support.

2. In a loom weft replenishing mechanism having a bobbin compartment and a pivoted

- cradle having a bobbin supporting portion positioned to control the delivery of bobbins from the compartment toward transfer position, a bobbin support pivoted to the replenishing mechanism and having a downwardly inclined surface, and an auxiliary guide extending from the support and being of less width than the support and lying closely adjacent to but out of the path of the supporting portion as the cradle pivots, said guide extending into the path of a bobbin which is passing from the cradle toward the support to guide the bobbin onto the support, the bobbin engaging surface of the auxiliary guide extending above the guiding surface of the support.
3. In a loom weft replenishing mechanism having a bobbin compartment and a pivoted cradle having a bobbin supporting portion positioned to control the delivery of bobbins from the compartment toward transfer position, a bobbin support pivoted to the replenishing mechanism and having a downwardly inclined surface, and an auxiliary guide extending from the support and being of less width than the support and lying closely adjacent to but out of the path of the supporting portion as the cradle pivots, said guide extending into the path of a bobbin which is passing from the cradle toward the support to guide the bobbin onto the support, said auxiliary guide extending to a point approximately under the horizontal center of the bobbin compartment.
4. In a loom weft replenishing mechanism having a bobbin compartment and a pivoted cradle having a bobbin supporting portion positioned to control the delivery of bobbins from the compartment toward transfer position, a bobbin support pivoted to the replenishing mechanism and having a downwardly inclined surface, and an auxiliary guide extending from the support and being of less width than the support and lying closely adjacent to but out of the path of the supporting portion as the cradle pivots, said guide extending into the path of a bobbin which is passing from the cradle toward the support to guide the bobbin onto the support, said auxiliary guide being movable with the support as the latter pivots and being out of contact with the cradle in all angular positions.
5. In a loom weft replenishing mechanism having a bobbin compartment and a cradle positioned to control the delivery of bobbins from the compartment toward transfer position, a bobbin support pivoted to the replenishing mechanism and having a downwardly inclined surface, and an auxiliary guide extending from the support and being of less width than the support and extending into the path of a bobbin which is passing from the cradle toward the support to guide the bobbin onto the support, the upper surface of the auxiliary guide being above the bobbin guiding surface of the support and extending beyond the upper part of the adjacent portion of the support to engage the wooden part of the bobbin before the rings of the bobbin engage the main support and to guide the rings gradually onto said main support.

In testimony whereof I have hereunto affixed my signature.

BENJAMIN W. BROUWER.
